ABSTRACT OF THE DISCLOSURE

A method of promoting osteogenesis in animal hosts which comprises applying to the area of a bone defect a quaternary ammonium compound of the formula

wherein R represents lower alkyl, X represents chlorine or bromine, and n is an integer from six to twelve; or of the formula

wherein R⁴ represents an alkyl group containing twelve to twenty carbon atoms; R¹, R² and R³ each represent lower alkyl, and R¹, R² and R³ taken together with the nitrogen atom represent pyridinium; and X represents chlorine or bromine.

This invention relates to a method of promoting osteogenesis in animal hosts which comprises applying to the area of a bone defect or disorder a quaternary ammonium compound. Quaternary ammonium compounds which may be administered to warm-blooded mammals in accordance with the method of this invention comprise compounds of the formula

I

wherein R represents lower alkyl, X represents chlorine or bromine, and n is an integer from six to twelve; or of the formula

II

wherein R⁴ represents an alkyl group containing twelve to twenty carbon atoms; R¹, R² and R³ each represent lower alkyl, and R¹, R² and R³ taken together with the nitrogen atom represent pyridinium; and X represents chlorine or bromine.

The term lower alkyl as employed herein includes both straight and branched chain radicals of less than eight carbon atoms. Preferred compounds for use in accordance with this invention comprise compounds of Formula I in which all four R groups represent methyl, and compounds in accordance with Formula II wherein R represents a straight chain alkyl group.

Compounds of Formula I may be prepared by a two-step process. In the first step, a polymethylene dichloride or dibromide containing six to twelve carbon atoms is reacted with a di(lower alkyl)amine in the presence of a solvent such as absolute alcohol to produce a corresponding polymethylene-bis-di(lower alkyl) amine. This is then reacted in the second step of the process with an equimolar amount of the polymethylene dihalide to produce the quaternary ammonium compounds of this invention.

For use, the quaternary ammonium compounds of this invention are preferably suspended in a sterile physio-

2

logical saline, e.g., about 2.0 to about 60 mg./ml. This is administered by injection into the area immediately adjacent or surrounding the site in the animal host (e.g., rats, dogs, cats, cattle, horses), at which it is desired to promote or stimulate bone growth, for example, at the site of bone implants, fractures, or in various metabolic bone defects (osteoporosis), or application to the periodontal tissue. In general, about 1 to 30 mg., preferably about 2 to 5 mg. of osteogenic agent per kg. of body weight is injected. This may be repeated one or more times as required. Alternatively, in the case of bone implants, a solution (for instance, 1 mg./ml.) can be made in sterile water and implant material can be saturated therewith as by immersion before being used in the patient.

The following examples illustrate the invention, all temperatures being in degrees centigrade.

EXAMPLE 1

(a) Bis-1,10-dimethylaminodecane

20 Into a pint-sized pressure bottle were placed 30.0 g. of 1,10-decamethylene dibromide, 18.0 g. dimethylamine, and 150 ml. absolute alcohol. The bottle was sealed and allowed to stand for five days. It was heated intermittently to 50°. The contents were poured into a 2.1. Erlenmeyer flask and diluted with 750 ml. anhydrous ether. A crystalline material was obtained, dimethylamine hydrobromide. It was removed by filtration and the filtrate was concentrated. The residue was distilled to give 17.5 g. of product, B.P. 143–146° (8 mm.).

30 (b) 1,1,12,12-tetramethyl-1,12-diazacyclodocosane dibromide

35 Into a pressure bottle were placed 16.9 g. of the product of Example 1(a), 24.3 g. decamethylene dibromide and 150 ml. acetone. The mixed materials were allowed to stand twelve days. The product was filtered and recrystallized from 200 ml. absolute alcohol and 1200 ml. acetone to give 27.9 g. of product, M.P. 193–194°. The product is quite hygroscopic.

EXAMPLE 2

1,1,8,8-tetramethyl-1,8-diazacyclotetradecane dibromide

40 Following the procedure of Example 1(b) but substituting 17 g. of bis-1,6-dimethylaminohexane for the bis-1,10-dimethylaminodecane and 24.5 g. of hexamethylene dibromide for the decamethylene dibromide, there is obtained 27 g. of product, M.P. 252.5–253.5°.

EXAMPLE 3

Sr⁸⁵ assay of osteogenic agents

45 The osteogenic agents of this invention are assayed by suspending a 60 mg. sample in 1 ml. of physiological saline and the pH is adjusted within the range of 6 to 7.

50 The osteogenic agent thus suspended is injected (0.1 ml., 6 mg. dose) along the periosteal surface of the radius-ulna complex of male rats weighing 180–200 g. The contralateral radius-ulna complex serves as the control. The rats are maintained for one week at which time 2 micro curies of radioactive Sr⁸⁵, preferably as Sr⁸⁵ nitrate, is injected intrathoracically. On the following day the animals are sacrificed and the Sr⁸⁵ content of the treated and control radius-ulna complex is measured. The assay depends upon the enhanced ability of newly formed bone (matured osteoid) to bind Sr⁸⁵ in addition to that bound by the pre-existing bone. The extent of bone growth induced within the week by osteogenic material is determined by calculating the difference in uptake of Sr⁸⁵ as calculated by the following expression:

$$70 \frac{\text{Sr}^{85} \text{ content of treated radius-ulna complex}}{\text{Sr}^{85} \text{ content of control radius-ulna complex}} \times 100$$

A value of 100 corresponds to no excess incorporation of Sr^{85} in the treated complex as compared with the control. Values above 100 give a measure of the degree of osteogenic potency of the materials (per mg. of dose) injected.

New bone production is always accompanied by a soft tissue reaction. This reaction varies with the material used to induce osteogenesis and may be separated histologically into an acceptable and an unacceptable category.

An acceptable tissue reaction is described as follows: Eight days following the injection of the osteogenic factor preparation there exists shrinkage and lysis of some muscle bundles. There is an influx of large numbers of fibroblasts associated with considerable new blood vessel formation. These fibroblasts (precursor cells) are non-differentiated; however, some do differentiate into osteoblasts in the area of new bone formation. A few giant cells are usually present in these areas and no indication of abscess formation exists. The new bone formation is quite extensive and occurs radially around the radius and ulna. The new bone is not compact but appears to be cancellous in nature with the formation of many discrete bone marrow cavities. This is the type of histological response which accompanies normal bone formation (e.g., repair of fractures).

Abnormal undesirable tissue reactions are described as follows: Eight days following the injection of certain substances there is shrinkage, lysis and necrosis of many muscle bundles. Abscess formation exists accompanied by massive tissue destruction. Fibroplasia does occur; however, it is not extensive. New bone formation occurs radially around the radius and the ulna. Resorption of the original shaft of the radius and ulna exists, often accompanied by rechanneling of the marrow cavity.

The Sr^{85} ratio and histological response observed in rat legs injected with compounds of this invention are tabulated below. In all cases, the histological response is acceptable, the new bone formation being cancellous in nature with the formation of many discrete bone marrow cavities. No resorption of the original bone shaft has taken place.

Compound	Dose (mg./kg.)	New bone (Sr^{85} ratio)	Fibroplasia	Undifferentiated cells	Giant cells	Necrosis	Abcess formation
$\text{CH}_3 - (\text{CH}_2)_{10} - \text{N}^+ - \text{N}^+ - (\text{CH}_2)_{10} - \text{CH}_3 - \cdot 2 \text{Br}^-$	2.9	267	Extensive...	Yes-----	Yes-----	Yes-----	None-----
$\text{CH}_3 - (\text{CH}_2)_{10} - \text{CH}_3$							
$\text{CH}_3 - (\text{CH}_2)_6 - \text{N}^+ - \text{N}^+ - (\text{CH}_2)_6 - \text{CH}_3 - \cdot 2 \text{Br}^-$	2.3	330	do-----	Yes-----	No-----	do-----	Do.

This invention may be variously otherwise embodied within the scope of the appended claims.

What is claimed is:

1. A method which comprises administering by injection to the area of a bone defect in an animal, in an amount effective to promote osteogenesis, a quaternary ammonium compound selected from the group consisting of compounds of the formula

wherein R represents lower alkyl, X is selected from the group consisting of chlorine and bromine, and n is an integer from six to twelve, and compounds of the formula

wherein R^4 represents an alkyl group containing twelve to twenty carbon atoms; R^1 , R^2 , and R^3 are each lower alkyl; R^1 , R^2 , and R^3 taken together with a nitrogen atom is pyridinium; and X is selected from the group consisting of chlorine and bromine.

2. A method in accordance with claim 1 wherein the compound administered has the formula

wherein R, X and n are as set forth in claim 1.

3. A method in accordance with claim 1 wherein the compound administered has the formula

25 wherein R^1 , R^2 , R^3 , and R^4 and X are as set forth in claim 1.

4. A method in accordance with claim 1 wherein the quaternary ammonium compound is administered in an amount of from about 1 to about 30 mg. per kg. of body weight.

5. A process in accordance with claim 2 wherein the compound administered is 1,1,12,12 - tetramethyl-1,12-diazacyclodocosane dibromide.

6. A method in accordance with claim 2 wherein the compound administered is 1,1,8,8-tetramethyl-1,8-diazacyclotetradecane dibromide.

7. A method in accordance with claim 3 wherein the compound administered is hexadecyltrimethylammonium bromide.

40 8. A method in accordance with claim 3 wherein the compound administered is 1-hexadecylpyridinium chloride.
